UNITED STATES PATENT OFFICE

JOSEPH BOCA, OF FLINT, MICHIGAN, ASSIGNOR TO GENERAL MOTORS CORPORATION,
OF DETROIT, MICHIGAN, A CORPORATION OF DELAWARE

METAL RUNNING BOARD

Application filed November 24, 1926. Serial No. 150,529.

This invention relates to running boards for use on automotive vehicles, and particularly to the manner in which the metal mat and its binding strips are attached.

5 In addition to neatness of appearance, inexpensive production and ease of construction, the object of the invention is to allow a more facile application of mats to running boards and permit of a ready replacement of parts should they become damaged or worn. It is also the object to construct a mat which will be held in place by a minimum of bolts or similar securing means and to secure the mat and its associated parts 10 to the apron which covers the space between the running board and chassis.

In the drawing:

Figure 1 is a side elevation, with parts broken away, of a portion of an automobile 20 sufficient to show the application of my invention thereto.

Figure 2 is a transverse section through the running board on line 2—2 of Figure 1.

Figure 3 is a plan view of a portion of mat 25 forming the object of my invention.

Figure 4 is a detail sectional view on an enlarged scale on the line 2—2 of Figure 1.

Referring to the drawings, 1 designates the running board as a whole, 2 the apron, 30 3 the side bar of the chassis, and 4 the rigid metallic supporting braces which are attached to the chassis at 5 and sustain the running board structure. These parts, together with the bolts 6 for fastening the board 1 35 to the braces, are conventional.

My invention is more closely concerned with the application of the mat 7 to the running board 1. This mat is of metal, but obviously may be of rubber, or any suitable 40 material, is flat on its under surface and has its top surface corrugated or provided with ribs 8 which extend the entire length of the mat. These ribs 8 form a rough surface and thereby permit of a more secure footing for 45 ingress to and egress from the vehicle.

Between the braces 4 and the mat 7 a metallic reinforcing and securing plate 9 is provided. This plate has its inner and outer edges downwardly flanged at 10 and 11 respectively, the outer flange 11 being return-

bent at 12, slightly spaced from the web of the flange 11, and then inwardly flanged as at 13, where it overlies but does not contact with the mat 7.

At the inner edge of the plate 9 where the 55 downturned flange 10 meets the apron 2, this apron has an outwardly bent flanged edge 12' which underlies the edge of the flange 10. Secured between the flange 10 and the apron 2 is a retaining strip 13', corrugated or ribbed 60 at its exposed surface. This strip is angle shaped and through one leg 14, through the flange 10 and the apron 2 a bolt 15 is passed and a nut 16 applied to rigidly secure the parts together. The other leg 17 has a downwardly bent flanged edge 18 which overlies and firmly contacts with the mat 7 to securely 65 hold it in place. If desired, the flange 18 may be omitted.

At each end of the mat 7 a suitable retaining strip 19 is provided to securely hold its transverse edges. The construction at the ends is the same as at the front except that the securing strip 19 has no bead but a reinforcing plate 26 is applied to the downturned 70 edge of the fender 27.

At the outer edge of the running board there is applied the longitudinal retaining strip 20 which is generally angle shaped. This strip is corrugated or ribbed as at 75 21 80 on its upper exposed surface and has a bead 22 stamped in its lateral surface. Both legs of the strip 20 have their longitudinal edges rounded and slightly return-bent and as a whole the strip 20 embraces the return-bent flange of the plate 9. The lower return-bent portion 23 closely conforms the return-bent edge of the plate 9, while the flange 25 of the upper rounded edge 24 fits around and is 85 held by the flange 13 and contacts with and securely holds the edge of the mat 7. This construction has the advantage of carrying the finish strip 20 well back from the outer edge of the running board thereby serving 90 to remove any great tendency for the shoe 95 of the passenger to strike the strip and tear it loose.

If desired the lateral beaded surface of the retaining strip 20 may be plain or corrugated. 100

gated, or in place of the ribs 21, a bead may be used.

In operation the plate 9 is first applied, the mat 7 laid thereon, the retaining and finishing strips 13 and 19 set in place and these parts secured together by means of the bolts 15 and nuts 16. The rounded edge 24 of the retaining strip 20 is applied under the flange 13 and the strip then snapped into place by pressing the rounded edge 23 over the edge of the flange 11, 12. I may also leave the edge 23 straight and bend the metal about the flange 11, 12 by means of a suitable tool.

Running boards are usually secured to their supporting braces by means of bolts but in my invention I apply these bolts in a novel manner. By referring to Figure 2 it will be noted that the plate 9 is countersunk as shown at 28 to receive the tapered head 29 of the bolt 6 which projects within the channel 32 of the brace 4. The head of the bolt is therefore flush with the upper surface of the plate. A U-shaped washer 30 having flanges 31 abuts against the bottom of the channel 32 and the nut 33 secures the washer on the bolt and holds the structure to the braces. The U-shaped washer has a certain amount of resiliency and when the nut is drawn tight the washer will have a tendency to push downward and thereby aid in more firmly securing the parts in place and prevent rattling.

What I claim is:

1. A running board, means to support the board, a plate mounted on said means, downturned flanges at the longitudinal edges of said plate one of said flanges being return-bent and inwardly flanged at its edge, a mat mounted on the plate, and retaining strips for securing the mat to the plate.

2. A running board, means for supporting the board, a plate mounted on said means, flanges at the longitudinal edges of said plate, one of said flanges being return-bent and inwardly flanged at its edge, a mat mounted on said plate and underlying said last named flange, and retaining strips embracing the flanges and securing the mat to the plate.

3. A running board, means to support the board, a plate mounted on said means, downturned flanges at the longitudinal edges of the plate, one of said flanges being return-bent and inwardly flanged at its edge, a mat mounted on the plate and underlying the last named flange, and angle shaped retaining strips embracing said flanges for securing the mat to the plate, one of said strips having rounded return-bent edges.

4. A running board, means to support the board, a mat, a plate mounted on said means and receiving said mat, downturned flanges on the longitudinal edges of said plate one of said flanges being return bent and slightly spaced from the web portion, a flange at the edge of the return-bent portion said last named flange overlying the mat, and inner

and outer angle shaped retaining strips embracing the flanged edges and mat edges for securing the mat to the plate.

5. A running board, means to support the board, a mat, a plate mounted on said means and adapted to receive said mat, flanges on the longitudinal edges of said plate, one of said flanges being return-bent and spaced from the web of the flange, a flange at the edge of the return-bent portion, said last named flange overlying the edge of the mat, and inner and outer angle shaped retaining strips embracing the flanged edges and overlapping the mat edges, said inner retaining strip having a downwardly projecting flange at its mat retaining edge.

6. In a running board, supporting means therefor, a plate mounted on said means, flanged edges on said plate, a return bent portion on one of said flanges, a mat on said plate, said mat underlying said return bent portion.

7. The combination of claim 6, said return bent portion having a flanged edge which overlies the mat.

8. The combination of claim 6, and a finishing strip secured to said return bent portion and holding said mat in place.

9. In a running board, supporting means therefor, an apron, a plate overlying said means, a flanged edge on said plate said flange secured to the apron, a second flanged edge, a return bent portion on said second flanged edge having an inwardly extending flange, a mat underlying the inwardly extending flange, and finishing strips secured to said flanged edges and holding said mat.

In testimony whereof I affix my signature.
JOSEPH BOCA.
